William Parker, Jr. INVENTOR
BY Victor J. Evans
ATTORNEY

UNITED STATES PATENT OFFICE

WILLIAM PARKER, JR., OF BEN AVON, PENNSYLVANIA

SHIRT

Application filed May 28, 1930. Serial No. 456,698.

This invention relates to improvements in shirts, the general object of the invention being to provide a pocket at one of the front ends of the collar band of the shirt for receiving a collar button so that the button is prevented from contacting the neck of the user and danger of the button dropping from the band is eliminated.

This invention also consists in certain other features of construction and in the combination and arrangement of the several parts, to be hereinafter fully described, illustrated in the accompanying drawings and specifically pointed out in the appended claim.

15 In describing the invention in detail, reference will be had to the accompanying drawings wherein like characters denote like or corresponding parts throughout the several views, and in which:

20 Figure 1 is a view of the improved band for the shirt, with the parts slightly separated to show the construction of the band.

Figure 2 is a section on line 2—2 of Figure 1.

25 Figure 3 is a section on line 3—3 of Figure 1.

Figure 4 is a section on line 4—4 of Figure 1.

Figure 5 is a fragmentary view of a shirt 30 with the improved band thereon.

As shown in these views, I form a pocket A at one of the front ends of the neckband B of the shirt C, with the buttonhole D passing through one wall of the pocket so that when 35 a collar button is passed through the buttonhole, the base of the button will be located in the pocket so that said base cannot contact the neck of the user and danger of the button accidentally leaving the buttonhole is practically eliminated. The collar band is preferably formed as usual of the two folded strips 1 having their upper edges turned inwardly, as shown at 2, and sewn together by the stitching 3, with a short folded strip 4 placed between the central portions of the strips 1, with its upper edges folded and sewn 40 between the upper edges of the strips 1, as shown in Figures 1 and 3. This strip 4, when the parts are sewn together, forms a pocket for the rear collar button which passes

through the buttonhole 5 formed in the outer strip 1.

In carrying out my invention, I place a short folded strip 6 at the right hand end of the band between the strips 1 with its upper ends folded and sewn by the stitches 3 to the upper edges of the strips 1, so that when the band is sewn to the shirt, as shown at 7, the pocket A is formed in the right end of the band to receive the base of the 55 collar button passing through the buttonhole D.

As shown in Figure 5, the stitches 7 fasten the lower edge of the small strip 6 to the inner strip 1 of the band so that this strip 6 forms the inner wall of the pocket, the pocket A in this case being formed on the outside of the band. If desired the strip 6 can be sewn to the outer strip 1 of the band, but in this event, the buttonhole D 60 must pass through the strip 6. In this case, the pocket A is formed on the inside of the band. Of course, if desired, the strip 6 can be omitted and the pocket formed either on the outside strip or the inside strip, depending on which is desired, by sewing the shirt to either the inside strip or the outside strip when the band is sewn to the shirt. The omission of this strip cheapens construction, but it is preferable to use the strip, to give 65 a neater appearance of the collar band when it is sewn to the shirt. The left buttonhole 8 is made as usual.

If the pocket A is to be formed on the outside of the band, the shirt should be placed 70 between the inside strip 1 and the short strip 6 and these parts sewn together, whereas if the pocket is to be formed on the inside of the band, the shirt should be placed between the outside strip 1 and the short strip 6 and 75 these sewn together.

The pocket can also be formed at the top of the band at the right end of the collar band by leaving the opening at the top of the band when the collar is made, in a similar manner to that at the bottom, with the buttonhole on the outside strip of the band. However, when this construction is used, the strips of the collar band are sewn together at the bottom when the band is sewn to the shirt, 80 85 90 95 100

thus leaving the opening through which the collar button is placed in the pocket at the top of the band.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A shirt band consisting of inner and outer strips each folded upon itself to provide closely related walls with some of their edges folded back upon themselves to provide attaching portions and said attaching portions engaging the inner walls of the respective strips, a third strip folded upon itself to provide closely related walls with some of their edges folded upon themselves and in opposite directions to provide attaching portions engaging between the first named attaching portions with the third strip positioned between said inner and outer strips and extending from one end of the latter to a point adjacent the other end, stitching securing said attaching portions together, said inner and outer strips adjacent one end having aligned slots and stitched together about said slots to provide an end buttonhole, said outer strip adjacent the end remote to said buttonhole and at a point intermediate the ends thereof provided with slots to form another end buttonhole and a back buttonhole, said third strip overlying the last named end buttonhole and the back buttonhole to prevent collar buttons when inserted therethrough from contacting with the neck of a person.

40 In testimony whereof I affix my signature.

WILLIAM PARKER, Jr.
